UNITED STATES PATENT OFFICE.

BURT NEULON PIERCE, OF FLINT, MICHIGAN.

CARBURETER.

1,366,831.

Specification of Letters Patent. Patented Jan. 25, 1921.

Application filed February 18, 1915. Serial No. 9,029.

To all whom it may concern:

Be it known that I, BURT NEULON PIERCE, a citizen of the United States, residing at Flint, in the county of Genesee and State

5 of Michigan, have invented certain new and useful improvements in Carbureters; and I do hereby declare the following to be a full, clear, and exact description of the invention, such as will enable others skilled 10 in the art to which it appertains to make and use the same.

The invention relates to improvements in carbureters, and more particularly to that type of carbureter especially designed for 15 use in connection with internal combustion engines.

The primary object of the invention is to improve the construction of carbureters, and the invention is particularly an improvement 20 on the carbureter constructions shown and described in my former applications for Letters Patent of the United States, No. 917,125, April 6, 1909; No. 973,877, October 25, 1910; No. 982,297, January 24, 1911; No. 25 1,005,300, October 10, 1911; and Canadian Letters Patent, No. 145,779, February 4, 1913.

Another object of the invention is to provide means for regulating the operation of 30 carbureters by controlling the exit therefrom of the gas passing to the engine.

A further object of the invention is to provide the controlling means, aforesaid, with a comparatively wide range of adjustment 35 whereby the carbureter may be regulated to a great nicety and exactness so that an engine can be started or stopped very slowly, gradually and noiselessly.

A still further object of the invention is 40 to provide such carbureter controlling means which admits of a slight, quick, initial starting charge to the engine, and a more gradual feeding and shutting off of the charge to be supplied to the engine under 45 operating conditions other than that of starting.

A more remote object of the invention is 50 to provide such carbureter controlling means wherein usual clattering of the control valve, common in the ordinary type of carbureter, is eliminated, the said control valve being so mounted that all unnecessary leakage therearound is practically obviated, while, however, the same is capable of adjustment 55 to permit the passage of sufficient mixture to constitute a priming charge, which, with

the gas admitted through the valve on its initial opening, forms an efficient charge for the slow starting of the engine, as may be, or is, desired.

With these and other objects in view, the invention resides in the certain new and novel constructions and arrangement of parts to be hereinafter more fully described, set forth in the appended claims, and illustrated in the accompanying drawings; in which:

Figure 1 is a front elevation of the carbureter showing the preferred form of controlling means as applied thereto,

Fig. 2 is a rear elevation,

Fig. 3 is an end elevation,

Fig. 4 is an end elevation opposite to that shown in Fig. 3,

Fig. 5 is a top plan view,

Fig. 6 is a bottom plan view,

Fig. 7 is a vertical longitudinal section on the line 7—7 of Fig. 5,

Fig. 8 is a horizontal section on the line 8—8 of Fig. 1,

Fig. 9 is a horizontal section on the line 9—9 of Fig. 1,

Fig. 10 is a detail plan view of the valve controlling means showing the method of mounting the governor arms on the valve shaft,

Fig. 11 is a detail view of one of the governor arms,

Fig. 12 is a vertical transverse section on the line 13—13 of Fig. 1,

Fig. 13 is a detail elevation showing the spring for controlling the air valve.

Reference being had to the accompanying drawings, in which like characters of reference designate corresponding parts on the several views thereof, the carbureter comprises a casing —15— formed with a central vertically disposed bore to provide a mixing chamber —16— which terminates at its upper end with a reduced bore to provide 100 an outlet —17— which is surrounded with a jacket —18—, preferably formed integral with the casing, to provide an annular passage or pocket —19— for the reception of a suitable heating medium to be admitted 105 thereto through the connection —20—, which heating medium is, preferably, the hot exhaust gases from the engine. After flowing through the pocket —19—, the heating medium passes to an outlet —21— and thence 110 through a discharge tube —22—, disposed vertically of the casing and discharging

downwardly, to atmosphere. A suitable plug —23— is threaded into an opening formed in the jacket —18—, at a point diametrically opposite the connection —20—, to permit access to the pocket —19— for the purpose of clearing the same of such foreign matter as may collect therein. A pair of threaded openings —24—, disposed at opposite sides of the outlet —17—, are provided so that the carbureter may be coupled to the adjacent end of the usual connection (not shown) leading to the engine manifold.

Interacting valves —25— and —26— are provided for controlling the outlet —17— and the connection —20—, respectively, the same being interconnected by means of a rod —27— to an operating lever —28—, and are so arranged that, when the valve —25— is fully opened, the valve —26— is tightly closed to prevent the heating medium from passing through or into the pocket —19—, or, in other words, the amount or volume of the heating medium admitted to the pocket —19— varies inversely with the volume of the gas it is desired to pass through the outlet. The valve —25—, of the outlet —17—, is mounted on a shaft —29— which has its opposite ends projecting through the casing —15— to support, at one end, a stop —30— adapted to contact a lug —31— when the valve —25— is in full open position, while the other end carries the lever —28—, aforesaid, which is formed to provide the oppositely disposed stops —32— and —33— adapted to contact a lug —34—, formed on the casing —15—, as is also, the lug —31—, aforesaid, when the valve —25— is in either its full open or closed position.

Diametrically opposite the lower portion of the casing —15—, and offset therefrom, are formed a float chamber —35— and an air inlet —36—, the former having an open top adapted to receive a cover —37— secured thereon by means of the several screws —38—, and is shaped, at its outer end, to provide a restricted portion —39— in the bottom of which is threaded a gasoline, or other liquid fuel, inlet connection —40— formed at its inner end to provide a needle valve seat —41—. Formed in the opposite walls of the restricted portion —39—, immediately adjacent its juncture with the float chamber —35—, are the bearings —42— in which is supported or threaded a pintle —43— upon which is carried a lever —44— upon one end of which is secured a float —45— and upon the other of its ends is secured a depending needle —46— adapted to have its lower end moved into and out of engagement with the valve seat —41— of the inlet connection —40— when the float —45— is raised or lowered by a corresponding rise or fall of the liquid fuel in the float chamber. Should the float —45—, for any ordinary reason, become sluggish in its opera-

tion, a member —47—, carried by the cover —37—, is provided to jar the same loose, a handle —48— being formed on the outer end of the member —47— for the operation of the same against the tension of a coiled spring —49— surrounding the member and interposed between the handle —48— and a collar —50— secured to the cover, and stop pin —51— is inserted through the member —47— to limit the latter the desired distance it is required to operate.

The air inlet —36— is provided with a disk valve —52— formed with a slight cut-away portion —53— to permit the passage of a small quantity of air to the mixing chamber —16— when the valve is in its closed position, and is carried by a shaft —54— having one of its ends projected through the wall of the inlet to support an actuating lever —55—. A coiled spring —56— is interposed between the lever —55— and the wall of the inlet and arranged in a manner suitable for maintaining the valve in normally open position, which is determined by a stop —57—, formed with the casting —15—, being engaged by the said actuating lever.

For the purpose of introducing the liquid fuel into that part of the centrally disposed bore of the casing —15—, hereinbefore designated as the mixing chamber —16—, a removable head —58— is adapted to be inserted into the bore, to the rear of the aforesaid mixing chamber —16— and is clamped in proper position by means of the screws —59— threaded into openings formed in the shoulders —60— of the casing. A threaded opening —61— is provided in the bottom wall of the float chamber —35— to receive the threaded end of a strainer plug —62—, after the latter has been passed through an opening formed in a depending portion —63— of the head —58—, the strainer plug —62—, when in engagement with the threaded opening —61—, acts as a further securing means for clamping the head —58— in position with respect to the casing. The plug —62— is provided with a longitudinal passage —64—, extending for a portion of the length thereof, and a transverse passage —65— in communication with the passage —64— and having its opposite ends opening through the bottom wall of a circular groove —66— formed on the circumference of the plug —62—, the open end of the passage —64— being covered with a strainer —67— of fine mesh wire screen, or other suitable straining material. The head —58— is provided with a centrally disposed passage —68— which establishes communication between the circular groove —66— of the plug —62—, the main or low speed injector nozzle —69—, and the auxiliary or high speed nozzle —70—, the said main injector nozzle —69— being arranged to discharge the main

supply of liquid fuel to one side of the mixing chamber —16—, while the auxiliary injector nozzle —70— is arranged to discharge a suitable amount of the liquid fuel to the other side of the mixing chamber —16—, as and for the purpose to be hereinafter set forth. Projecting from the inner face of the head —58— is a semi-cylindrical body —71— having a curved cut-away portion —72—, the purpose of which will be hereinafter fully explained. An opening —73— is provided in the flat face —74—, of the body —71—, to permit passage therethrough of a current of air to and through a circular space —75—, surrounding the main injector nozzle —69—, to the mixing chamber.

Intermediate the ends of the main injector nozzle —69— is formed a valve seat —76— adapted to receive the adjacent end of a needle stem —77— which is adjustably threaded in a nipple —78— projecting outwardly from the outer face of the head —58—. The nipple —78— is exteriorly threaded to receive a cap-nut —79—, surrounding the needle stem —77—, adapted to retain and compress a packing ring —80— tightly around the needle stem —77— to prevent possible leakage of the liquid fuel therefrom.

The head —58— is provided with a second offset portion —81— which is provided with an enlarged bore —82— to receive the adjacent end of the discharge tube —22—, aforementioned, a closure —83—, pivoted at —84—, being provided to regulate the exit of the heating medium through the bore —82— to atmosphere. A small opening —85—, however, may be formed in the cover or closure —83—, to prevent the absolute closing of the bore against the passage of the heating medium therethrough.

To initially heat the liquid fuel passed through the injector nozzles —69— and —70—, a duct —86— connects the bore —82— with a circular passage or pocket —87— formed in the semi-cylindrical body —71—, which surrounds the main injector nozzle —69—, and, the heating medium, after passing through the pocket —87—, is discharged therefrom through the opening —88— formed in the outer wall of the head.

Extending diametrically across the mixing chamber —16— is a valve-shaft —89—, supported at its opposite ends in suitable bearings —90— and —91—, and provided intermediate its ends with a slot —92— in which is supported an air proportioning flap-valve —93—, which may be held in any desired adjusted position therein, with respect to the curved cut-away portion —72—, of the semi-cylindrical body —71—, of the head —58—, by means of the screws —94—, the said flap-valve —93— being adapted for proportioning the amount of air to be ad-

mixed with the liquid fuel within the mixing chamber.

One end of the valve-shaft —89— is projected beyond the bearing —91— to support an arm to provide two sections —95— and —96— of a valve controlling mechanism, the abutting faces of the two sections —95— and —96— being provided each with a series of serrations —97—, by means of which, the two sections may be adjusted in any desired angular relation with respect to one another, and are clamped, in such adjusted relation, by means of a nut —98— threaded on the projecting end of the valve-shaft. The arm section —95— is provided with a reduced extension —99— upon which is to be supported for sliding adjustment a weight —100—, retained in its desired adjusted position, by means of a securing element —101— fitted into a bore formed intermediate the ends of the top face of the weight —100—, and having an opening formed therethrough adapted to align with the transverse opening, in the weight, which receives the extension —99—, of the arm section —95—. The securing element —101— is provided with a reduced threaded shank, not shown, upon which is placed a washer —103— and is threaded a nut —104—.

It is to be noted that the weight —100— is preferably positioned, on the extension —99—, so that its resistance to the opening of the flap-valve —93— is least at the initial movement of the latter and gradually increases until full open position of the same is attained, since the center of gravity of the weight —100— is substantially in a vertical plane passing through the center of axis —89— and it is obvious that it requires less effort to move a pendulum through a given arc when the weight is directly under the point of support than at any other position and the farther the weight is swung from the perpendicular the greater the effort required to move it through a given arc. The arm-section —96— is pivoted at its outer end, as at —105—, to the upper end of a rod —106—, which is also pivoted at its lower end, as at —107—, to a piston —108—, the latter operating in a dash-pot cylinder —109—, in the lower portion of which is positioned a coiled spring —110— of a length slightly less than the distance between the bottom of the cylinder and the under face of the piston, when the latter is in its normal or inoperative position. The space, thus provided between the piston and spring, admits of an initial and substantially unrestricted movement of the former which corresponds to the initial opening of the flap-valve —93—, as has been hereinbefore described.

A stop rod —120— is projected from the inner wall of the casing and into the mixing chamber —16— for the purpose of limiting

the movement of the flap-valve —93—, when the same has reached its full open position, which, it will be observed, is in the plane of the longitudinal axis of the bore, of the 5 casing, in advance of the semi-cylindrical body —71—, of the removable head —58—, and disposed centrally between the main injector nozzle —69— and the auxiliary injector nozzle —70—.

10 The condition of the carburetor, when at rest, or when inoperative, is as follows:— Considering the carburetor as being properly connected for operation, as usual, the throttle valve —25—, the air valve —52—, 15 and the flap-valve —93— being in their normally closed positions, and the float chamber —35— filled with its supply of liquid fuel, a required quantity of the latter being free to pass to the auxiliary injector nozzle 20 —70— which projects into the air inlet side of the mixing chamber —16— and behind the flap-valve —93—, where it mixes with the incoming air upon the opening of the inlet valve 52, while a major portion of the 25 same is led to the low speed injector nozzle 69 and mixes with an air supply coming from the air inlet 36 through the passage 75 surrounding the nozzle 69 for the purpose. The flap valve 93 is adjustably mounted 30 within the slot 92 of the valve shaft 89, as clearly shown.

When it is desired to start the engine, the same is cranked for the purpose, and after the throttle valve —25— has been moved to 35 open position, the primary charge is drawn from the main or low speed injector nozzle —69— and the air passage 75, (the needle-valve —77— having been adjusted to establish communication between the float chamber 40 and the main nozzle) by reason of the suction set up by the moving pistons in the engine cylinders. Such suction, aforementioned, immediately causes a slight rapid initial opening of the flap-valve —93—, due 45 to the fact that such initial movement or opening obtains practically without any resistance to the same on the part of the weighted arm —95—, and also, by reason of the fact that piston —108—, in the dashpot cylinder —109—, is permitted a slight 50 free movement before acting to place the coiled spring —110— under tension.

As the engine gradually picks up speed, resistance to the further opening of the flap-valve —93— increases gradually in a corresponding proportion to the increase of mixture it is desired to be passed to the engine manifold, since the weight —100—, in the first instance, is carried by the arm —95—, 60 away from its normal inoperative position in a plane perpendicular to and below the pivot point of the arm —95—, on the shaft —89—, and the piston —108— engages the coiled spring —110— to place the latter 65 under tension.

Upon the opening of the flap valve 93, fuel is drawn through the auxiliary or high speed nozzle 70 simultaneously with the flow of air now drawn direct from the air inlet, while the suction effect is decreased correspondingly upon the main or low speed nozzle 69. 70

When it is desired to stop the engine, the throttle valve —25— is closed, in the usual manner, thus cutting off the charge from 75 the cylinders and, therefore, the suction created in the latter, and when this is accomplished, the flap-valve —93— returns automatically to its normally closed position, at first, in a rapid manner, and thereafter more slowly and gradually with the lessening of the force of gravity of the weighted arm, as in either case beforementioned, as well as the decrease in the tension of the now expanding coiled spring acting on the piston, to its normally inoperative position. 80 85

By properly manipulating the disk valve —52—, of the air inlet —36—, any desired amount of air may be admitted to the mix- 90 ing chamber, as usual.

By coupling the engine exhaust (not shown) in any suitable manner to the connection —20—, an efficient heating of the gas, as it passes to the manifold of the engine, is obtained, and, as has been hereinbefore explained, a valve —26— is provided, in the connection —20—, for regulating the amount of hot gases, from the exhaust, or other heating medium which 100 may be employed for the purpose in lieu of such exhaust gases, in suitable proportions to properly condition the fuel or gas before the same is passed to the manifold. 100

From the foregoing it is readily observed 105 that the invention provides for a comparatively simple, compact, and efficient carburetor construction, and a regulating means for the same which admits of the desired quick initial feeding of a sufficient quantity 110 of mixture to start an engine slowly, and a more gradual proportional admixture of air with the same during the picking up in speed of the latter, and one in which, by reason of a gradual increase or decrease of 115 resistance to the opening and closing of the proportioning flap-valve —93—, the usual clattering or uncontrolled movement of the latter is entirely eliminated.

Having thus fully described the invention, 120 what is claimed, is:—

1. A carburetor comprising a casing provided with a bore forming a carbureting passage having an air inlet at its lower end, a body arranged within said casing having 125 a passage through which air is adapted to pass, a low speed nozzle extending into the passage of said body, a pivoted suction controlled valve arranged in said casing adapted to be normally held in contact with the op- 130

posite wall of said bore for normally closing a portion of said passage, a high speed nozzle extending into said bore having its upper end arranged adjacent the wall of said bore and terminating adjacent the free end of said valve in a plane above the level of the low speed nozzle.

2. A carbureter comprising a casing provided with a bore having a lateral air inlet at its lower end and provided with means at its upper end for connecting the same to an internal combustion engine, a body arranged within said bore having a passage through which air is adapted to pass, a low speed nozzle extending into said passage and terminating below the upper end of said body, a suction controlled valve arranged in said casing adapted to be normally held in contact with the opposite wall of said bore for normally closing a portion of said passage and a high speed nozzle extending into the bore of said casing having its upper end arranged adjacent the wall of said bore and terminating adjacent the free end of said valve.

3. A carbureter comprising a casing provided with a bore to provide a mixing chamber, said bore having a lateral air inlet communicating therewith, a removable head for closing the lower end of said bore carrying fuel nozzles, a suction controlled valve arranged over one of said fuel nozzles and means for controlling the opening and closing movement of said valve, said means being substantially inoperative during the initial opening movement of said valve, increasing its resisting effort to the subsequent opening of said valve to its full open position, rapidly operating to return the valve to its partially closed position and thereafter more slowly and gradually to its normally closed position.

4. A carbureter comprising a casing formed to provide a mixing chamber having an air inlet opening through its wall adjacent its lower end and an outlet opening centrally of the top of the same, a head arranged at the rear of said mixing chamber, spaced injecting nozzles projecting from said head and discharging into said mixing chamber, a semi-cylindrical body formed on

the inner wall of said head having a curved cut-away portion provided at its outer end and a pivoted valve located in said mixing chamber between said nozzles and adjustably mounted with respect to said cut-away portion of said semi-cylindrical body, said valve normally closing communication between said mixing chamber and one of said nozzles and said air inlet.

5. A carbureter comprising a casing having a bore forming a mixing chamber and having an air inlet at one end thereof, a fuel chamber carried by said casing, a head for closing one end of said bore having a fuel passage communicating with the fuel chamber, said head being provided with a body having a vertical and horizontal air passage, fuel nozzles carried by said head communicating with the fuel passage thereof, one of said fuel nozzles being disposed within the vertical air passage of the body of said head and the other fuel nozzle extending into said bore having its upper end arranged adjacent the wall of said bore and terminating in a plane above the air inlet, and a suction controlled valve mounted in said bore over the upper end of said last mentioned nozzle.

6. A carbureter comprising a casing having a vertical bore forming a mixing chamber, said casing having a lateral air inlet at its lower end communicating with said bore, a fuel chamber carried by said casing, a detachable head for closing the lower end of said bore, a body carried by said head having a vertical and horizontal air passage, said head having a fuel passage communicating with the fuel reservoir, a low speed nozzle carried by said head extending into the vertical air passage of said body, a high speed nozzle carried by said head extending into said bore and terminating in a plane above the air inlet thereof, and a suction controlled valve arranged over said high speed nozzle and adjacent thereto.

In testimony whereof I affix my signature, in presence of two witnesses.

BURT NEULON PIERCE.
